FRED SAYLES, OF LOS ANGELES, CALIFORNIA

SHOE STRAIGHTENER

Application filed May 6, 1930. Serial No. 450,188.

This invention relates to a shoe straightener adapted to be placed on the outside of a shoe. Shoe straighteners heretofore used have required insertion in the shoe and fill the latter. They are cumbersome, difficult to insert and comparatively expensive. Shoes which are damp or wet are more in need of a shoe straightener than dry shoes. However, handling of a damp shoe is objectionable and as a result the conventional shoe straighteners remain unused when their need is greatest. Furthermore, the conventional shoe straightener by reason of filling the shoe does not give the shoe an opportunity to dry or air out.

The present invention pertains to a shoe straightener arranged to be engaged with the toe end of a shoe, passed under the outsole and in engagement therewith and at the rear secured at the heel end of the shoe leaving the inside freely accessible to air for drying and ventilation. By such a structure the tendency is to flex and bend the sole in a direction opposite to the curvature attained by walking and thus to place the upper in tension especially at the vamp where wrinkles occur. The objects of this invention are to provide a shoe straightener meeting the aforementioned requirements and having the following features: economy of structure; applicability to either the right or left shoe; compactness and simplicity; lightness in weight and ease of manipulation.

These objects together with other objects and corresponding accomplishments are obtained by means of the embodiment of my invention illustrated in the accompanying drawings, in which:—

Fig. 1 is a side elevation of a shoe with my improved straightener applied thereto; Fig. 2 is a plan view of the straightener removed from the shoe; and Figs. 3 and 4 are sections through the straightener as seen on the lines 3—3 and 4—4 correspondingly marked of Fig. 1, the outsole being shown fragmentarily in Fig. 4.

Referring more particularly to the drawings, the straightener shown is a skeletal frame generally of U form with a waist intermediate the front and rear ends. It is

preferably formed of resilient wire provided with a yoke 5 at its front end offset laterally from arms 6. The arms are bent intermediate their ends to provide the waist portion and fastened by a girdle of sheet metal 7. However, it will be understood, that any other suitable mechanical expedient may be resorted to in order to produce the waist. The arms at the rear of the waist diverge from one another to provide spring clamp arms 60 marked 6a and 6b. The arms 6a and 6b are turned inwardly toward one another and in overlapping relation to form jaws 7a and 7b. The ends of the jaws are provided with upwardly turned portions ending in lips 8a 65 and 8b adapted to engage the lip of the toe of the shoe adjacent the heel.

In applying the straightener to the shoe, the yoke 5 is placed over the lipsole at the toe of the shoe and passed under the outsole. 70 The waist 7 rests against the outsole and the arms 6a and 6b of the clamp are pressed inwardly to expand the jaws and permit the lips 8a and 8b to be engaged over the lipsole of the shoe adjacent the heel. In its normal 75 condition, the frame is substantially flat. The action of the tree is a tendency to flex the sole in the opposite direction to its curvature which results from walking and thus places the upper of the shoe under tension especially at the vamp portion.

It will be understood, that in its broad aspect, the rear of the frame may be clamped to any suitable portion at the heel end of the shoe and the structure varied to adapt itself to gripping the particular heel portion. Furthermore, it will be understood that I do not limit myself to the particular construction whereby the toe end of the shoe is engaged. Any form of frame engaging the toe end, the outsole on its under portion and the shoe at the rear tending to flex the shoe comes within the purview of my invention as will be apparent from the subjoined claims.

What I claim is:—

1. A shoe straightener adapted to be placed on the outside of a shoe comprising a frame having a toe portion to be engaged with the toe end of a shoe sole, said frame comprising resilient members extending from the oppo- 100

site ends of the toe member rearwardly beneath the sole of the shoe in converging and then in diverging relation, clamps on the rearward ends of said members for engaging the sole, and a plate carried by the resilient members at their point of convergence and divergence and holding said members in their assembled relation.

2. A shoe straightener adapted to be placed on the outside of a shoe comprising a frame having a toe yoke arranged to extend across, overhang and to be engaged with the toe end of a shoe sole, said frame comprising resilient members extending from the opposite ends of the toe member rearwardly and offset downwardly from the toe portion to be disposed beneath the sole of the shoe in converging and then in diverging relation, clamps on the rearward ends of said members for engaging the sole, and a plate carried by the resilient members at their point of convergence and divergence and holding said members in their assembled relation.

In witness that I claim the foregoing I have hereunto subscribed my name this 7th day of April, 1930.

FRED SAYLES.
